CLAIM

The ornamental design for a nail polisher for pets, as shown
and described.

DESCRIPTION

FIG. 1 is a first perspective view of the nail polisher for pets
showing my new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an exploded view thereof.

The broken lines illustrate portions of the nail polisher for
pets that form no part of the claimed design.

1 Claim, 7 Drawing Sheets
